UNITED STATES PATENT OFFICE.

WILLIAM H. ROSE, OF JERSEY CITY, NEW JERSEY, ASSIGNOR TO RODIC RUBBER CO., OF GARWOOD, NEW JERSEY, A CORPORATION OF NEW JERSEY.

CONTAINER CLOSURE.

Application filed March 16, 1925. Serial No. 15,841.

To all whom it may concern:

Be it known that I, WILLIAM H. ROSE, a citizen of the United States, residing at Jersey City, county of Hudson, and State 5 of New Jersey, have invented new and useful Improvements in Container Closures, of which the following is a full, clear, and exact specification.

My invention relates to container closures 10 and refers particularly to closures suitable for use in combination with collapsible tubes.

Collapsible tubes are especially suitable for containing pastes, such as tooth paste, 15 shaving creams and similar products, because of their adaptability in allowing the removal of a predetermined or desired quantity of contents in a physical form for effective application upon a brush.

20 In the uses above indicated, it is necessary that the paste be emitted in the form of a ribbon of flat or round construction, that the removal be of a forced character, that the emission may be interrupted when 25 so desired and that the container be capable of practically complete closure when not in use, for economic, hygienic and practical purposes.

Another essential feature in a container 30 of the described character is that the closure means be permanently attached to the container during use, in order that it may not be lost or misplaced.

Another important feature of such device 35 is that a practically complete closure be accomplished when not in use, in order that the contents may not become dry or affected by dust or atmospheric conditions.

Still another important feature of such 40 devices is that the closure be of such construction that it will not become clogged with the contents during non-use in such a manner that the emission of the contents is later accomplished with difficulty.

45 The device of my invention possesses all of the above, and other, desirable features, as will be evident upon a consideration of the accompanying drawings and the description of my invention.

50 In the particular form of the device of my invention shown in the accompanying drawing, similar parts are designated by similar numerals.

Figure 1 is a perspective view of one form

of my device incorporated in a collapsible 55 tube.

Figure 2 is a vertical cross-section of Figure 1 showing the tube in open position.

Figure 3 is the same as Figure 2, showing the tube in closed position. 60

Figure 4 is a side view of the form of my device shown in the other figures.

The particular form of the device of my invention shown in the accompanying drawings comprises a rubber tubular member, or plunger, 10, open at its lower end and carrying the externally positioned annular closure member 11 with an upper shoulder 12. The upper end 13 of the tubular member 10 is closed and extends outwardly to 70 form the annular top 14, which is in turn extended downwardly forming the flange 15 spaced from the main tubular member 10. The tubular member has an opening 16.

The device is positioned within the collapsible tube 17, having the shoulder 18 and the neck 19 as shown in the accompanying drawings. 75

The device in a closed position is shown in Figure 3, the hole 16 being within the tube 80 17, and the flange 15, the top 14 and the upper portion 13 of the device forming a tight jointure with the neck 19 of the tube 17, preventing the escape of the tube contents. 85

When it is desired to obtain the contents of the tube, the device is pulled outwardly into the position shown in Figure 2, the shoulder 12 of the closure plug 11 abutting upon the shoulder 18 of the tube, thus causing a closure between these elements. If, now, the tube 17 be partially collapsed by means of pressure applied thereto, the contents 20 will be forced outwardly through the tubular member and the opening 16. 90 95

When it is desired to again close the tube the pressure is removed, and the device pushed inwardly to the position shown in Figure 3.

In the form of the device illustrated in 100 the drawings, the device is composed of rubber of such pliability as to allow of complete closure by compressed contact as shown and of such rigidity as to allow of its inward and outward movement within the 105 neck of the container.

It will be seen from the above, that my device comprises a container closure, ca-

able of movement within the neck of the container, the inward position of which closes the container and the outward position of which opens the container, the device having means for sealing the jointure between the container and the device when the container is in open position, the whole device being always maintained in combined position with the container and preventing its accidental removal therefrom.

It is to be noted that when the closure device is moved inwardly, the neck 19 of the tube removes all excess paste from the exterior of the plunger and from around the hole 16, thus preventing an accumulation of paste which might dry upon long discontinued use and thus, so seal the hole 16 as to make it difficult to force the paste therethrough.

20 While I have referred particularly to collapsible tubes and paste contents, it is evident that my device may be advantageously applied to rigid containers and for use with liquids.

25 I do not limit myself to the particular size, shape, number, material or arrangement of parts as shown and described, as these are given simply as a means for clearly describing my invention.

30 What I claim is:—

1. In a container closure in combination, a tubular slidable plunger of resilient material open at one end and closed at the other end and having an opening in a side thereof and an exterior shoulder upon the open end portion of the plunger, the closed end of the plunger having a spaced circumferential flange.

2. A container closure capable of insertion through the exterior opening of a container neck, comprising a tubular slidable plunger of soft rubber open at one end and closed at the other end and having an opening in a side thereof, an exterior shoulder upon the open end portion of the plunger capable of abutment against the interior face of the container shoulder when the device is in outward position, and a spaced circumferential flange upon the closed end portion of the plunger capable of abutting upon the exterior face of the container neck when the device is in inward position.

3. A container closure capable of insertion through the exterior opening of a container neck, comprising a tubular slidable plunger of soft rubber open at one end and closed at the other end and having an opening in the side thereof, an exterior shoulder upon the open end portion of the plunger capable of abutment against the interior face of the container shoulder when the device is in outward position, and a spaced circumferential flange upon the closed end portion of the plunger capable of abutting upon the exterior face of the container neck when the device is in inward position, the contents of the container being capable of egress through the side opening of the plunger when the device is in outward position and prevented from egress therethrough when the device is in inward position.

Signed at New York city in the county of New York and State of New York this 10th day of March, 1925.

WILLIAM H. ROSE.
